UNITED STATES PATENT OFFICE.

JOSEPH FIALA, OF NEW YORK, N. Y., ASSIGNOR TO STANDARD PNEUMATIC ACTION COMPANY, OF NEW YORK, N. Y., A CORPORATION OF NEW YORK.

SUCTION-PUMP.

1,161,383.

Specification of Letters Patent. Patented Nov. 23, 1915.

Application filed April 8, 1914. Serial No. 830,342.

To all whom it may concern:

Be it known that I, JOSEPH FIALA, a citizen of the United States, residing at New York, in the county of New York and State 5 of New York, have invented a new and useful Suction-Pump, of which the following is a specification.

This invention relates to a suction pump and more specifically to a device of this 10 character particularly adapted for clearing the air tubes and tracker bar of a pneumatic player action.

It is the principal object of my invention to provide a suction pump of this type 15 which is more convenient in use and more effective in operation than the devices heretofore used for this purpose.

My invention accordingly consists in the provision of an improved device for guiding 20 and alining the pump with the tracker bar and for preserving such alinement during the operation of the pump, together with improved details of construction by which the pump is adapted to coöperate with the 25 tracker bar in a most convenient manner.

A preferred form of my invention is shown in the drawings in which—

Figure 1 is a side view of a suction pump 30 partially broken away to show the interior construction; Fig. 2 is a plan view of the pump taken in a plane at right angles to that of Fig. 1; and Fig. 3 is a partial end elevation of the pump.

As shown in the drawings, the suction 35 pump comprises a body member 10 having an end portion 11 formed integral therewith and having a movable member 12 connected to the end portion 11 by a hinge 13. The portions 10 and 12 are provided with operating handles 14—14 and the two parts are 40 connected by the usual bellows member 15. An opening 16 through the movable member is covered with a loose leather flap 17, these parts forming a suction valve of the 45 usual form. The end portion 11 is provided with a passage 18 which is elongated in cross section as shown in Fig. 3.

As above stated, this suction pump is 50 designed particularly for cleaning the air tubes and tracker bar of a pneumatic player action. Certain of these air tubes are indicated at 19, the tubes being directly connected with the tracker bar 20. The front

face of the tracker bar is usually formed with a convex surface 21 in order that the 55 music sheet may be drawn easily thereover, coming in close contact with the bar at the point at which the tubes 19 are connected thereto.

In order that the suction pump may fit 60 closely over the tracker bar and may co-operate therewith in a more effective manner than has been heretofore attained, I form the outer end of the portion 11 with a concave surface 22 corresponding in curvature 65 to the face of the tracker bar. I also provide the portion 11 with a projecting lip 23 adapted to rest upon the upper edge of the tracker bar. The lip 23 and the surface 22 may be provided with a cushion covering 24 70 of rubber or felt.

When the lip 23 rests upon the upper surface of the tracker bar 20, the pump will be supported in the relative position shown in Fig. 1, in which position the passage 18 75 is alined with the tubes 19 and the pump can most effectively operate to clear the tubes. At the same time, the concave surface 22 fits closely over the convex surface of the tracker bar, making it easy to secure a good 80 contact between the parts and to prevent the admission of air into the bellows except as it is drawn through the tubes 19.

Having thus described a preferred form 85 of my invention I do not wish to be limited to the precise details herein disclosed, but

What I claim is:—

1. A bellows for cleaning the tracker bar of a musical instrument comprising a body portion having an air passage through one 90 end thereof and having a handle fixed to the opposite end thereof, and a movable bellows leaf hinged to said body portion and having a handle fixed to the free end thereof, said body portion having a projecting lip 95 adjacent the end of said air passage, said lip being adapted to rest against one side of the tracker bar and being effective to position the air passage of the bellows in horizontal alinement with the openings of the 100 tracker bar as the bellows is moved longitudinally of said bar.

2. A bellows for cleaning pneumatic player actions having, in combination, a body portion with an air passage through one end 105 thereof, and means for inducing air tension

through said passage, the end of the body portion being provided with a projecting lip which is effective as a gage to aline the air passage in the bellows with the holes in the tracker bar of the action to be cleaned, said end also having a concave contacting surface corresponding substantially to the curvature of the tracker bar.

In testimony whereof I have hereunto set my hand, in the presence of two subscribing ¹⁸ witnesses.

JOSEPH FIALA.
